UNITED STATES PATENT OFFICE.

JAMES F. BRODERICK, OF CHICAGO, ILLINOIS, ASSIGNOR TO TROY LAUNDRY MACHINERY COMPANY, OF CHICAGO, ILLINOIS, A CORPORATION OF NEW YORK.

DRYING-TUMBLER.

1,323,673.

Specification of Letters Patent.

Patented Dec. 2, 1919.

Application filed July 3, 1919. Serial No. 308,500.

To all whom it may concern:

Be it known that I, JAMES F. BRODERICK, a citizen of the United States, residing at Chicago, in the county of Cook and State 5 of Illinois, have invented certain new and useful Improvements in Drying-Tumblers, of which the following is a specification.

This invention relates to an apparatus for drying laundry articles, and operates upon 10 the principle of agitating the articles in a reticulated drum or cylinder, through which is driven a body of air in suitable condition to absorb the moisture from the articles, as, for instance, by first forcing the body of air 15 under a suitable head of pressure through a heating and drying chamber, and thence to the cylinder.

Under some conditions, it is desirable to discharge the air after it passes through the 20 cylinder; while in others, for the sake of economizing in heat units, it becomes desirable to circulate the air repeatedly through the machine, as, for instance, by feeding the air-forcing device, mainly or 25 wholly, with air that has passed through the cylinder. But when the air is thus used repeatedly, it becomes very important to de-lint the air, or strain out the fibers which it picks up in the cylinder, and thus prevent 30 the fibers from accumulating around the bearings of the apparatus or being returned and deposited upon the articles in the cylinder.

The object of the present invention is to 35 provide a machine which is conveniently convertible for operation in either of the two ways above named. Accordingly, the invention consists in providing in a machine of the class described, a delinting chamber 40 having a lint-arresting screen through which air from the drying cylinder can pass in reaching the air-forcing device by which it will be returned through the drying chamber to the cylinder; and having also an im- 45 perforate shutter that is adapted to replace the screen, or overlie or underlie the same in a manner to arrest the passage of air from the delinting chamber to the air-forcing device, and thereby cause the air to escape 50 from the delinting chamber through another channel, as, for instance, that usually provided for discharge of the lint that accumulates in the delinting chamber. Different methods may be followed in substituting the 55 shutter for the screen, or introducing the

shutter into and out of position in which it will arrest the passage of air through the screen, but this is preferably accomplished by arranging the shutter to slide into and out of position after the manner of a drawer, 60 the screen being similarly arranged so that it may be removed after the shutter is placed in position, particularly if it should be desired to subject the screen to a cleaning operation while out of the machine. 65

The invention will be fully understood upon reference to the accompanying drawing, in which—

Figure 1 is a vertical sectional view of a 70 drying tumbler; and

Fig. 2 is a section on the line 2—2 of Fig. 1.

The machine herein disclosed for the purpose of illustrating the present improvement is that forming the subject-matter of an 75 application filed March 31st, 1919, in the name of William Bartholomew, Serial No. 286,334, and which comprises a drying tumbler 1 having a reticulated cylindrical wall 1^a with a door 1^b by which to introduce and 80 remove articles to be dried; a casing 2 which surrounds the cylinder and which is provided with a door 2^a through which to gain access to the door 1^b; an opening 3 which leads through the wall of the cylinder from 85 a drying chamber 4; an air trunk 5 leading from a blower 6; a suction chamber 7 from which air is drawn into the blower 6; and a delinting chamber 9 into which the air passes from the drying cylinder, and which 90 is provided with a discharge port 9^a for lint accumulating therein, a screen 10 through which air with the lint arrested therefrom may pass from the delinting chamber into the suction chamber, and a 95 sweep 11 adapted to traverse the inner surface of the screen 10 to transfer to the discharge port the lint accumulating on the screen.

According to the present invention, an 100 imperforate shutter 12 is applied over the space occupied by the screen 10, as, for instance, by sliding the shutter in the guides 12^a after the manner of a drawer. The shutter is preferably located along the un- 105 der side of the screen as shown, as it permits the action of the sweep 11 to continue over the arresting surface of the screen after the shutter is introduced. The screen is also preferably mounted in guides 10^a which 110

adapt the screen to be withdrawn while the shutter is in place, in case it is desired to clean or repair the screen. Obviously, the shutter and screen could be fitted in the same guides, as, for instance, by withdrawing the screen and then inserting the shutter, or by having the tracks of the guides continue through the machine, so that by introducing the shutter at one end the screen 10 is forced out at the other end, and vice versa, and one member thus substituted for the other without leaving the wall between the chambers 7 and 9 unprotected at any time.

15 With an equipment as above-described, when operating in a relatively cold atmosphere or under other conditions which make it desirable to circulate air through the machine, using the same air repeatedly together with such increment as may be necessary, and which may be taken in as needed through the intake 14 in the chamber 7; or, when operating in a relatively warm atmosphere so that economizing in heat units 20 or other conditions make it unnecessary to circulate the air, introduction of the shutter, either as a substitute for the screen 10 or as a deadening closure therefor, will cause all the air to be discharged through the port 9^a 25 after being used, a constantly fresh supply of air being taken in through the intake 14. There is a further advantage in combining the shutter 12 with the screen 10 in the arrangement described, in that by temporary introduction of the shutter and interruption of the passage of air through the screen, the sweep 11 will operate to much 30 better advantage in removing the lint from the screen.

35 40 I claim:

1. In a drying tumbler having an air-circulating channel and a delinting chamber provided with a screened opening through which it delivers air to the circulating channel, an impervious shutter adapted for closing said opening and arresting the flow of air therethrough.
2. In a drying tumbler having an air-circulating channel and a delinting chamber 50 provided with a screened opening through

which it delivers air to the circulating channel, an impervious shutter adapted for closing said opening and arresting the flow of air therethrough; said opening being adapted to receive both the screen and the 55 shutter.

3. In a drying tumbler having an air-circulating channel and a delinting chamber provided with a screened opening through which it delivers air to the circulating channel, an impervious shutter adapted for closing said opening and arresting the flow of air therethrough; said opening being 60 adapted to receive both the screen and the shutter with the screen exposed to the sweep while the shutter is in position.

4. In a drying tumbler having an air-circulating channel and a delinting chamber 70 provided with a screened opening through which it delivers air to the circulating channel, an impervious shutter adapted for closing said opening and arresting the flow of air therethrough; said opening being 75 adapted to hold either the screen or the shutter at will.

5. In a drying tumbler having an air-circulating channel and a delinting chamber provided with a screened opening through 80 which it delivers air to the circulating channel, an impervious shutter adapted for closing said opening and arresting the flow of air therethrough; said delinting chamber having a port through which air discharges, 85 and said circulating channel having an intake through which air is admitted when the shutter is closing said opening.

6. In a drying tumbler having an air-circulating channel and a delinting chamber 90 provided with a screened opening through which it delivers air to the circulating channel, an impervious shutter adapted for closing said opening and arresting the flow of air therethrough; said shutter being 95 adapted to slide into and out of position to close said opening.

Signed at Chicago, Illinois, this 12th day of May, 1919.

JAMES F. BRODERICK.
